UNITED STATES PATENT OFFICE.

SIMEON W. PERRY, OF CHICAGO, ILLINOIS.

DESIGN FOR AN ADVERTISING-FRAME.

SPECIFICATION forming part of Design No. 32,099, dated January 9, 1900.

Application filed October 13, 1899. Serial No. 733,532. Term of patent 7 years.

To all whom it may concern:

Be it known that I, SIMEON W. PERRY, a citizen of the United States, residing at the city of Chicago, in the county of Cook and State of Illinois, have invented and produced a new and original Design for Advertising-Frames, of which the following is a specification, reference being had to the accompanying drawings, forming a part thereof.

Figure 1 is a front view of an advertising-frame, showing my new design; and Fig. 2 is an end view of the same.

As shown in the drawings, the leading or material feature of my design consists of a rectangular frame having sides, base, and top with the space between the sides, base, and top divided into a number of corresponding rectangular spaces and having a series of pockets arranged upon each side thereof vertically, one above the other.

In the drawings, A A represent rectangular compartments, which are separated by vertical strip B and by horizontal strips C C.

D D represent a series of pockets, which are arranged upon each side of the advertising-frame vertically, one above another.

Having described my invention, what I claim as new, and desire to secure by Letters Patent, is—

The design for an advertising-frame, as 30 herein shown and described.

In testimony whereof I have signed my name to this specification in the presence of two subscribing witnesses.

SIMEON W. PERRY.

Witnesses:

W. T. PERRY,
C. E. PICKARD.
